United States Patent Office

Des. 192,000
Patented Dec. 26, 1961

192,000

LUGGAGE CASE

Sol Koffler, 600 Blackstone Blvd., Providence, R.I.

Filed July 26, 1961, Ser. No. 66,075

Term of patent 14 years

(Cl. D87—5)

FIG. 2

FIG. 3

FIG. 1

The essential features of the design are shown in full lines.

I claim:

The ornamental design for a luggage case, as shown and described.
